UNITED STATES PATENT OFFICE.

ALONZO JOHNSON, OF SPRINGFIELD, MASSACHUSETTS, ASSIGNOR, BY MESNE ASSIGNMENTS, TO THE SPRINGFIELD ENVELOPE COMPANY, OF MASSACHUSETTS.

GUMMING DEVICE FOR ENVELOPE-MACHINES.

SPECIFICATION forming part of Letters Patent No. 397,798, dated February 12, 1889.

Application filed May 25, 1888. Serial No. 275,071. (No model.)

To all whom it may concern:

Be it known that I, ALONZO JOHNSON, a citizen of the United States, residing at Springfield, in the county of Hampden and State of 5 Massachusetts, have invented a new and useful Improvement in Gumming Devices for Envelope-Machines, of which the following is a specification.

The present improvement in envelope-machines relates to devices to be operated, in conjunction with the main gummer or picker, for the purpose of gumming a portion of one end of a flap of a high-cut-envelope blank, whereby, when said one end flap is folded 10 over to lie by its end over the end portion of the other end flap, it will be pasted thereto and at a portion thereof lying nearly up to the line of fold for the seal-flap, the back overlapping flap of the blank, as well known, usually overlapping and being secured to the 15 edges of the end flaps slightly; and the present invention consists in the combination and arrangement of the various parts, all substantially as will hereinafter more fully appear, 20 and be pointed out in the claims.

On reference to the accompanying sheets of drawings, in which the present invention is illustrated, and in which similar characters of reference indicate corresponding parts in all 25 of the views, Figure 1 is a side elevation of some parts at the front and top portion of an envelope-machine in connection with which the present independent gumming device is applied, some of the parts in said view being 30 shown as broken away and in vertical section for better illustration. Fig. 1^a is a horizontal cross-section of the device on line *a a*, Fig. 1. Fig. 2 is a front view of the parts shown in Fig. 1. Fig. 3 is an enlarged view of the improved gumming device by itself and as seen 35 from the opposite side thereof to that seen in Fig. 1. Fig. 4 is an enlarged back view of same, or a view as seen at the opposite side thereof to that seen in Fig. 2. Fig. 5 represents an envelope-blank for a high-cut envelope, the portion thereof gummed by the employment of the present invention being in-

dicated; and Fig. 6 is a rear view of an envelope, showing the end and back flaps folded in place and to be hereinafter referred to. 50

In the drawings, Figs. 1 and 2, A represents the front end of the usual table of the envelope-machine; B, the front arch, in which are the usual bearings for the plunger-shaft C, which carries the pickers or gummers D for 55 gumming the seal and back flaps of the envelope-blanks E, a pile of which in said figures is shown supported, as usual, on the platen F. The picker-plunger is reciprocated through the engagement with an attached strap thereon of one end of a link, *b*, which by its other end is connected to a crank-arm, *d*, on a horizontal rocker-shaft, G, supported in suitable bearings, *f*, and oscillated through the means of a crank-arm thereon and a connecting-rod actuated by a cam on the main shaft, (not shown,) all as usual, common, and well known in envelope-machines at present in extensive use, and the said parts are shown and herein mentioned as above that the relations 60 65 therewith of the devices of the present invention may be more readily ascertained. 70

Resting on a supplemental support or table, 10, above the table A is an upright, 11, secured thereto, for carrying and guiding the 75 operative parts of the present device, and having right-angled lugs 17 thereon at each end thereof, through vertical bearings of which slides a vertical rod, 13, on the intermediate portion of which rod is a clasp or slide-block, 80 14, pivoted to which intermediately thereof, as at 9, is a bar, 15, normally standing vertical and parallel with said slide-rod 13, spiral springs 16 16, secured to and reacting between the outer ends of said bar 15 and lugs 12 on 85 the ends of said slide-rod, serving to maintain said bar vertically and to maintain the said block 14 suspended midway between the ends of the slide-rod, so that on the block being moved either up or down the said rod is constrained to move therewith, and the said block 14 is extended through a vertical guide-slot, 18, in said upright, with which extended 90 portion thereof one end of a link, 19, is piv-

totally connected, its other end being pivoted to the outer end of a crank-arm, 20, on said oscillating shaft G. The said upright is provided with an extended vertical flange, 21, having therein a vertical slot, 22, of suitable length, through which passes forward the horizontal portion 23 of the independent gummer x, continued in a downward extension, 24, formed at its outer end with a gumming-face, 25, of a contour to cover the portion of an envelope-blank end flap, (indicated at 26, Figs. 5 and 6.) The upper end of the slot 22 serves as an abutment-stop for the gummer to limit and modify its movement, as will be explained in connection with the following description of the operation of the machine, and it will be apparent that the said end of the slot must be carefully located with relation to the throw of the gummer. As shown in the drawings, the picker D is nearly at its uppermost position, and the block 14 is slid up nearly but not quite into its uppermost position, so that the end face of the independent gummer x is front of and about level with the top of a gum-box, 27, properly adjusted in relation thereto. As the block 14 by the connection described with the oscillating shaft is moved slightly and still farther upwardly to its limit, the horizontal portion 23 of the gummer-arm x abuts against the upper end of the slot 22 in the flange 21, said arm tilting by its outer end downwardly, dipping into the gum-box to receive a quantity of gum on its face, the gummer with its bar 15 swinging on the pivot 9 of the block 14, and at such time causing a deflection of the springs 16, the action of which when the block is slid downwardly again will tend to carry the bar into its upright position, and when upright will maintain the gummer in its proper position for its straight downward projection against the blank, as seen in Fig. 1 and in the full lines, Fig. 3, the dotted lines in said latter figure illustrating the dipping movement of the gummer when raised; and, as will be noted in reference to said Fig. 3, the upper end, 30, of the said flange 21 is inwardly curved or projected toward the edge of the bar 15, which is recessed, as at 31, the upper edge of the recess being downwardly and inwardly inclined, as at 32, such formations securing on the downward throw of the slide-block a positive movement of the bar 15 into its upright position irrespective of the action of the sustaining-springs.

On the portion of the oscillation of the rocker-shaft G to secure the descent of the picker D the block 14 and pivotally-connected and spring-sustained gummer x are also carried downwardly, so as to be by its face pressed upon the indicated portion of the one end flap, securing a gumming thereof simultaneously with the gumming, as usual, by the picker of the back and seal flaps of the blank. As will also be noticed in Fig. 3, the bar 15 is provided with an extended edge

or flange, 34, which, in the up-and-down travel of the block 14, bar 15, and gummer, assists to steadily maintain said parts in their vertical relations, as described, and yet does not interfere with the dipping movements of the gummer and conjunctive parts.

While a particular arrangement of parts has been shown and described for spring-sustaining the gummer x, pivotally attached to the reciprocating slide, normally in line for presentation against the proper portion of the envelope-blank, and yet to permit of a tilt or dip of the gummer on its contact with an abutment suitably applied for such contact therewith toward its upward stroke, the invention is not to be limited to such particular form of spring-sustaining appliances, as other spring-acting devices may be applied between the pivoted gummer and its carrier for the similar effect.

What I claim as my invention is—

1. The combination, with an upright, of a vertically-reciprocating slide-block moving thereon, a spring-sustained gummer pivotally hung on said slide-block, an abutment on said upright arranged in the line of travel of said gummer to secure on the upward movement of said gummer a swing or dipping motion thereof, and the gum-box, substantially as and for the purpose described.

2. The combination, with the rocker-shaft G and crank-arm 20 thereon and a supporting-upright, 11, of a slide-block, 14, vertically movable on said upright and linked to said crank-arm, a spring-sustained gummer, x, pivotally hung on said block 14, an abutment on said upright arranged in the line of travel of said gummer to secure on the upward movement of said gummer a swing or dipping motion thereof, and the gum-box, substantially as described, for the purpose set forth.

3. The combination, with the rocker-shaft G, the crank-arm 20 thereon, and the upright 11, provided with the slide-bearing lugs 17, and having the flange 21, provided with the vertical slot 22, and also provided at its upper end with the inward projection 30, of the slide-block 14, vertically movable on said upright and linked to said crank-arm, the slide-rod 13, centrally embraced by said block and guided in said lug-bearings 17 and having the end lugs, 12, the bar 15, intermediately pivoted to said slide-block and provided with the inclined edge 32, the springs 16 between the ends of said bar and said lugs 12, the gummer x, rigidly attached to said bar 15 near its pivoted point and projecting through said slot, and the gum-box, all arranged for operation substantially as and for the purpose described.

4. The combination, with the rocker-shaft G and crank-arm 20 thereon and a supporting-upright 11, provided with the slide-bearing lugs 17 and having the vertically-slotted flange 21, of the slide-block 14, vertically

movable on said upright and linked to said crank-arm, the slide-rod embraced by said block and guided in said lug-bearings 17 and having the end lugs, 12, the bar 15, intermediately pivoted to said slide-block and having the flange 34, the springs 16 between the ends of said bar and said lugs 12, the gummer rigidly attached to said bar 15 near

its pivotal point, and the gum-box, all combined and arranged for operation substantially as and for the purpose described.

ALONZO JOHNSON.
